SOOT BLOWER FOR BOILERS

Elgin Blasdell, Flint, Mich.

Application October 21, 1939, Serial No. 300,503

1 Claim. (Cl. 122—392)

This invention relates to soot blowers and particularly to the provision of means for blowing the soot from between the tubes of a tubular boiler.

The invention makes use of a steam pipe penetrating the wall of the boiler and having discharge jets or openings adapted to deliver steam under pressure between the tubes of the boiler to remove the soot.

An object of the invention is to provide means to fixedly secure the steam pipe and thereby definitely lock the jets relatively to the boiler tubes.

Other objects and advantages will be understood from the description which follows.

In the drawing:

Figure 1 is a section through a boiler wall showing the boiler tubes therein and the steam pipe with the jets for cleaning the boiler.

Figure 2 is a view as seen from line 2—2 of Figure 1.

Figure 3 is a section on line 3—3 of Figure 2.

Referring by numerals to the drawing, a boiler wall is shown at 5 and within the boiler are the tubes 7. The space between the tubes accumulates soot for the removal of which there is provided means to deliver among the tubes steam under a pressure of perhaps 175 pounds per square inch.

To this end a steam pipe 9 extends through an opening 11 in the wall 5. The steam pipe 9 extends at right angles to the boiler tubes 7. The pipe 9 is suitably supported at the outer face of wall 5 by any convenient means designated on the drawing by numeral 13. At axially spaced positions in the steam pipe are openings or jets 15. The pipe 9 is so positioned that the jets or openings are located in the spaces between the boiler tubes. If these openings were closely adjacent the tubes the steam pressure might blow holes in the tubes.

The heat within the boiler tends to cause considerable relative movement between the boiler tubes and the steam pipe 9 and this movement may be sufficient to cause the jets to be moved to a position adjacent the tubes and damage the latter as explained above.

To avoid the damage referred to there is shown, in accordance with this invention, means to prevent such movement of the steam pipe 9 relative

to the boiler tubes. At 17 is a bracket. It is formed from two spaced side walls 19, with spaced upper and lower intermediate members 21 and 23 between the walls. The members 21 and 23 may be secured to the side wall as by welding, the welding being indicated by numeral 25. The bracket 17 extends lengthwise of one of the boiler tubes and is secured also by welding as indicated at 27. An anchor plate marked 29 is formed with a tongue 31 shaped to fit between the side walls and between the members 21 and 23. The anchor plate has a U-shaped opening formed by a curved portion 33 of circular outline from which diverge upper and lower extensions 35 and 37.

15 A ring 39 with an intermediate groove 41 is placed over and secured to the blower pipe 9 in a selected position. The walls of the ring 39 adjacent the groove fit around the curvilinear base portion 33 of the opening in the anchor plate as shown in the drawing. A retainer or cap 43 is shaped to fit between the extensions 35 and 37. It, too, has a curvilinear outline marked 45 to cooperate with a circular base part 33 and fits between the walls forming the slot 41. Suitable 20 fastening means 47 secure the cap to the extensions 35 and 37 and complete the support for the steam pipe 9.

With this construction the pipe 9 is fixedly located relative to the boiler tubes and damage 25 to the latter is avoided.

There is shown on the drawing at 51 a diagrammatic illustration of any suitable means whereby steam from a suitable source may be admitted to or cut off from the pipe 9. This invention is not concerned with the details of this valve control.

I claim:

For use with a boiler having tubes, a steam pipe for cleaning said boiler extending into said boiler and having jets, supporting means for said blower pipe secured to one of said tubes, said supporting means including a bracket secured to said tube, an anchor plate carried by said bracket and a removable cap adapted to be secured to said anchor plate, said blower pipe carrying a grooved collar and said anchor plate and cap having cooperating curvilinear parts adapted to be received within the groove of said collar.

ELGIN BLASDELL.
